(57) **CLAIM**

The ornamental design for an elastic band launcher, as shown and described.

DESCRIPTION

FIG. 1 is a perspective view of an elastic band launcher showing my new design;

FIG. 2 is a front view of the elastic band launcher of FIG. 1;

FIG. 3 is a rear view of the elastic band launcher of FIG. 1;

FIG. 4 is a side view of the elastic band launcher of FIG. 1, the opposite side being a mirror image;

FIG. 5 is a top view of the elastic band launcher of FIG. 1; and,

FIG. 6 is a bottom view of the elastic band launcher of FIG. 1.

The broken lines in the drawings illustrate the portions of the design that form no part of the claimed design.
